HEATING APPARATUS

Walter S. Landon and Philip S. Russel, Detroit,
Mich., assignors to Detroit Lubricator Company, Detroit, Mich., a corporation of Michigan

Application February 23, 1940, Serial No. 320,332

14 Claims. (Cl. 236—1)

This invention relates generally to new and useful improvements in heating apparatus and more particularly to means for controlling the operation of a liquid fuel burner.

One object is to provide an apparatus in which a reduction in the supply of oil to the burner precedes a reduction in the supply of combustion supporting air.

Another object is to provide a novel temperature responsive means for controlling the operation of a liquid fuel burner.

Another object is to provide auxiliary automatic controlling means for an automatically operated control device.

Another object is to provide an apparatus having an operating means normally controlled by a first actuating means and having a second actuating means for moving the operating means irrespective of the operation of the first actuating means.

Another object is to provide an apparatus having an operating means moved to one position by an actuating means and moved to a second position by a second actuating means.

The invention consists in the improved construction and combination of parts, to be more fully described hereinafter and the novelty of which will be particularly pointed out and distinctly claimed.

In the accompanying drawing, to be taken as a part of this specification, we have fully and clearly illustrated our invention, in which drawing—

Figure 1 is a schematic view of the apparatus embodied in a liquid fuel hot water heating apparatus, and

Fig. 2 is a view of a modification of a portion of the apparatus showing a new and improved heat motor.

Referring to the drawing by characters, the numeral 1 designates generally the casing of a constant liquid level device having a liquid receiving chamber 2 with an outlet valve port 3 which is adapted to be connected to a liquid fuel burner (not shown). A valve member 4 has a conical portion 5 which cooperates with the port 3 to control flow of fluid therethrough, and has an upwardly extending stem portion 6 extending through and guided within an aperture 7 in the top chamber wall 8 of the chamber 2. The valve member 4 is biased toward closed position by a helical coil spring 8^a interposed between the wall 8 and an annular flange 8^b of the member 4. Movement in the valve closing direction, however, is limited by the engagement of a flange 9

with a minimum flow stop member 10 adjustably carried by a bracket 11 of the casing 1 overlying the aperture 7. Upward or valve opening movement of the valve member 4 is limited by engagement of the flange 9 with a maximum flow stop member 12 adjustably carried by the bracket 11. The extreme upper end portion of the stem portion 6 is guided within a hollow boss 13 of the bracket 11.

10 A hook-shaped bimetallic power element 14 has an end portion 15 at the terminus of the curved part 16 and has a straight or lip part 18 having an end portion 17. The element 14 is preferably secured at its end portion 15 to a bracket 19 rigid 15 with the casing 1 and so positioned that the end portion 17 is operable to engage the underface of the flange 9 so that upon upward movement of the lip or straight part 18, the valve member 4 will be raised to permit flow of fluid through the 20 outlet port 3. An electrical heater element 20 is positioned within the element curved part 16 and upon energization acts to heat the part 16 which opens up, thereby moving the lip part 18 upward to engage the flange 9 and to lift the valve 25 member 4 against the stop member 12.

20 A second bimetallic power element 22, similar to the element 14, has a lip part 23 and a curved part 24 terminating in end portions 25, 26, respectively, and is rigidly secured to a supporting 25 member 27 at the portion 26. The member 27 is secured to the casing 1 in a manner similar to that of the element 19. The part 24 receives an electrical heater 28 which acts upon energization to cause the part 24 to open and the lip part 23 to move upward. Upward movement causes the part 23 to engage a downwardly extending protuberance 29 of a mercury tube switch holder 30 pivoted, as at 31, so that a mercury tube switch 32 carried thereby will be rotated to circuit closed 30 position. The switch 32 is biased toward open circuit position and into engagement with a stop member or pin 32^a.

30 An externally threaded, cup-shaped member 35 is screw-threaded into an aperture through a side wall of the reservoir 36 which contains the fluid heated by the fuel burner (not shown). The member 35 opens externally of the reservoir 36 and has an inner wall member 37 in good heat transfer relation with the reservoir fluid. A thermocstatic element 40, similar to that described and disclosed in Letters Patent No. 2,128,274, granted to Sergius Vernet and dated August 30, 1938, comprises a cup-shaped bottom casing member 41 having secured to its open end a flanged or flared portion 42 of a tubular shaped

upper casing member 43. A helical coil compression spring 44 is positioned within the member 35 concentric with the tubular member 43, and has one end abutting an externally threaded annular member 45 which also surrounds and is concentric with the tubular member 43. The other end of the spring 44 abuts the flange 42 and as the member 45 is screw-threadedly secured within the open end portion of the member 35, the spring 44 acts to hold the bottom wall of the cup-shaped member 35 against the wall member 37 and in good heat conductivity therewith. This particular construction also permits the element 40 to be held against the wall member 37 with a predetermined force irrespective, between certain limits, of the exact positioning of the member 45 with respect to the member 35. In this manner production tolerances may be increased to lower costs.

The temperature sensitive material, which is in this instance a material which undergoes a change in crystalline structure, thereby increasing in volume upon increase in temperature, is carried within the cup-shaped portion adjacent the bottom wall thereof, and the space overlying the sensitive material and underlying a diaphragm 46 is filled with a liquid which may be a concentrated solution of sodium silicate, and which acts to transfer the force exerted by the sensitive material to the diaphragm 46. This type of sensitive element is substantially non-responsive to temperature changes below a predetermined temperature, and then upon attainment of this predetermined temperature acts within a very narrow range of increased temperature to expand and do its work. A thrust rod 47 extends longitudinally through the tubular member 43 and has a flanged end wall 48 which is held against the outer side of the diaphragm 46 by a helical coil compression spring 49. The spring 49 is concentric with the thrust rod 47, and is interposed between an internal flanged portion of the tubular member 43 and the flange end wall 48.

A lever member 50 is fulcrumed, as at 51, on a rigid support 52 carried by the tubular member 43, and is pivoted to the thrust rod 47, as at 53, so that it may be rotated by the rod 47 in accordance with the expansion and contraction of the sensitive material. A connecting rod 54 has a lower end guided within the hollow boss 13 and is operable to abut the upper end of the valve member 4. An upper end portion 55 of the rod 54 is of reduced diameter, and is loosely received and guided within an aperture in the lever member 50 and is movable relative thereto. A helical coil compression spring 56 is concentric with the rod 54 and is held under compression between the lever member 50 and a shoulder 57 formed at the intersection of the reduced portion 55 with the normal diameter of the member 54 and acts to hold the lever member 50 in engagement with a nut 58 screw-threadedly secured to the rod portion 55. The spring 57 further acts as a lost motion or over-travel connection so that the lever member 50 can have continued rotation subsequent to engagement of the valve member flange 9 with the minimum stop member 10, thereby relieving the parts of any undue stress.

A mercury tube type switch 59 is carried within a holder 60 pivoted, as at 61, and biased toward open position. A downwardly extending protuberance 62 of the holder 60 normally engages a pin 63 carried by the rod 54 so that the

switch 59 is rotated to closed position upon upward movement of the rod 54. However, when the temperature of the fluid within the fluid containing reservoir 36 is at or above a predetermined temperature, the rod 54 is in its down position and the thermostatic element 40 is against a stop member or pin 63a in the position shown in Fig. 1 with the switch 59 in open position. Element 40 will move and/or hold valve member 4 against the minimum stop 10 irrespective of the operation of the element 14. Upon cooling of the fluid in reservoir 36, the element 40 will cool and move the rod 54 upward and through pin 63 move the switch 59 again to closed circuit position and place valve member 4 under the control of the element 14.

A switch 64, which may be a manually operable switch, as shown, or an automatically operable switch, such as a temperature sensitive switch responsive, for example, to room temperature, all of which are well known in the art, is supplied with electrical energy from a source of supply (not shown). A lead wire 65 connects one side of the mercury tube switches 32 and 59 with the switch 64, and a lead wire 66 connects the other side of the switch 59 with one side of the heater element 20. The other side of the heater element 20 is connected by a lead wire 67 to one side of the heater 28 and lead wire 68 connects the other side of the electrical heater 28 to the switch 64 so that upon closure of the switches 59 and 64, current will flow through lead wires 65, 66 to the heater element 20 and electrical heater 28 and back through the switch 64 to the source of energy. Current flowing through the elements 20 and 28 acts to heat the bimetal parts 16 and 24. Heating of part 16 moves the lip part 18 to raise the valve member 4 until flange 9 engages the stop member 12 and against the force of a spring 8a. The other side of the switch 32 is connected by a lead wire 69 to a motor 70, and by a lead wire 71 to lead wire 68, and through switch 64 to the source of supply. Heating of the part 24, due to energization of the element 28 by closure of the switches 59 and 64 causes the lip part 23 to engage the protuberance 29 and rotate the mercury tube switch 32 about its pivot 31 and into circuit making position. Electrical energy then flows from the switch 64, lead wire 65, switch 32, lead wire 69 to the motor 70 and back through lead wires 71 and 68 and switch 64 to the source of supply. The motor 70 in this instance is used to supply the necessary air for combustion of the fuel being admitted to the burner through port 3, but, however, may be some other form of electrically controlled equipment for cooperation with the fuel supplied through the port 3. A fuse 72 is inserted in the lead wire 68 intermediate the connection of lead wires 68, 71 and the switch 64, and acts to rupture the electrical circuit to both the motor 70 and elements 20, 28, in the event that the current flowing through lead wire 68 becomes excessive. The motor 70 is thereby stopped and the valve member 4 is moved to minimum flow position, or until flange 9 is in engagement with stop member 10.

Fig. 2 shows a modified form of the power elements 14, 22, and in which modification the elements 14, 22 have been fabricated from a single element 75 split longitudinally to form a pair of lip portions 76, 77 for actuating the valve member 4' and switch 32' respectively. The longitudinal split extends into the hook portion of the element 75 and terminates prior to but substan-

tially at the point where the hook portion is secured to the supporting member 19' to form a pair of hook portions 78, 79. These portions 78, 79 are heated by the same heater element 20' and therefore any variation in the output of the heater element 20' will affect the operation of both of the element lip portions 76, 77, and the relative time lag of operation between the two portions, 76, 77 will not be affected. The construction, as shown, in Fig. 2 will also alleviate the difficulties caused by variation between different heating elements which may be encountered in manufacture and also prevents a replacement of one matched bimetallic element by one which has a different characteristic.

The operation of the apparatus is as follows: Upon closure of the switch 64, electrical current flows from the source of supply through lead wire 65, switch 59, lead wire 66 into the heater element 20, lead wire 67, element 28 and lead wire 68 back to the source of supply. Passage of current through the elements 20, 28 causes the elements to heat up and warm the bimetal elements 14, 22 which act respectively to move the valve 4 to open position and the switch 32 to closed circuit position. The heater elements 20, 28 have been so chosen relative to each other and to the elements 14, 22 that the proper sequence of operation of the valve member 4 and the motor 10 is accomplished. The burner operates to raise the temperature of the fluid within the reservoir 36 but due to the peculiar characteristics of element 40, which is in good thermal relation with the fluid in the reservoir 36, no effect is noted until a predetermined temperature of the fluid in the reservoir 36 and of the element 40 has been reached. Upon the attainment of the predetermined temperature the crystalline material within the member 41 starts to change its physical state and expands forcing the diaphragm 46 outwardly. Outward movement of the diaphragm 46 acts through the thrust rod 47 to rotate the lever member 50 about its pivot 51 in a counterclockwise direction to move the rod 54 downward into engagement with the valve member 4. Continued movement of the diaphragm 46 moves the flange 9 of the valve member 4 into engagement with the minimum stop member 10 and at the same time the pin 63 is moved downward allowing the switch 59 to rotate into circuit breaking position. Continued movement of the lever member 50, due to continued expansion of the crystalline material, acts to compress the spring 57 for lost motion between the parts so that the parts are not unduly strained. Upon opening of the switch 59, the elements 14, 22 begin to cool and after a predetermined time, which in the case of a pot-type furnace, is sufficient to burn the remaining excess fuel, the element 22 will cool sufficiently to allow switch 32 to rotate to open circuit position, thereby to stop the motor 10. The element 14 upon cooling assumes a position disengaged from the flange 9 but no change in operation results because the valve member 4 is positively moved to minimum flow position against the valve opening force of element 14 by the stronger element 40.

It may be seen that the apparatus described is one which is operable to control a liquid fuel burner in a new and novel manner. The burner is supplied with fuel subsequent to the actuation of the heat actuated elements, which are so arranged that should one bimetallic heater element become inoperative, the other bimetallic element heater would fail to function and thereby

prevent an improper burner operation. The apparatus is also so arranged that upon the attainment of a predetermined temperature condition of the fluid heated by the burner, the fuel flow is reduced to a predetermined minimum flow and at a subsequent predetermined relative time the air supplying means is stopped. This apparatus also is constructed and arranged so that the fuel valve is not modulated throughout the temperature range of the heated fluid but acts substantially at a single temperature to move the valve to closed position, thereby allowing for the maximum burner output and consequent rapid rise in temperature of the heated fluid until the predetermined desired temperature is reached, after which time a very slight temperature increase rapidly moves the fuel valve to minimum fire position.

In Fig. 2 there is shown a new and improved bimetallic heat motor so constructed and arranged that it can actuate two means at a fixed relative relation therebetween irrespective of variation encountered in the actuating heat source and also will not act to operate a means without the subsequent actuation of the other means.

What we claim and desire to secure by Letters Patent of the United States is:

1. In an oil burner control, a fuel supplying valve means, an air supplying means, electrical means operable to exert a force on said valve means, said electrical means being operable upon exertion of said force to move said valve means toward open position and to start said air supplying means, and means engageable with said valve means and sensitive to the medium heated by said fuel and operable upon a predetermined temperature directly to move said valve means toward closed position against said force exerted by said electrical means and to deenergize said electrical means for stopping of said air supply subsequent to the closing of said valve means.

2. In an oil burner control, a fuel supplying valve means, an air supplying means, electrical means operable to move said valve means toward open position and to start said air supplying means, means sensitive to the medium heated by said fuel and operable upon a predetermined temperature directly to move said valve means toward closed position and to deenergize said electrical means for stopping of said air supply subsequent to the closing of said valve means, and means connecting said sensitive means and said valve means and having a lost motion portion, said lost motion portion acting to allow said valve means to be controlled by said electrical means below said predetermined temperature independently of said sensitive means.

3. In an oil burner control, a fuel supplying valve means, an air supplying means, electrical means operable to move said valve means toward open position and to start said air supplying means, means sensitive to the medium heated by said fuel and operable upon a predetermined temperature directly to move said valve means toward closed position and to deenergize said electrical means for stopping of said air supply subsequent to the closing of said valve means, means connecting said sensitive means and said valve means and having a lost motion portion, said lost motion portion acting to allow said valve means to be controlled by said electrical means below said predetermined temperature independently of said sensitive means, and means operable to

allow continued movement of said sensitive means subsequent to the closing of said valve means.

4. In an oil burner control, a fuel supplying valve means, an air supplying means, electrical means operable to exert a force on said valve means thereby to move said valve means toward open position said electrical means also being operable to start said air supplying means, means sensitive to the medium heated by said fuel and operable upon a predetermined temperature directly to move said valve means toward closed position against said force of said electrical means and to deenergize said electrical means for stopping of said air supply subsequent to the closing of said valve means, stop means limiting movement of said valve means in said open direction, and stop means to limit movement of said valve means toward said closed position.

5. In an apparatus of the character described, a first controlling means movable in two directions to control flow of fuel to a fuel burner, an electrical controlling means for supplying air to the apparatus, a thermostatic heat motor means operable to move said first controlling means in one of said directions, a thermostatic power element sensitive to the output of the fuel burner and operable to move said first means in a second of said directions against the force of said heat motor means, said power element also being operable to render ineffective said heat motor means, a second heat motor means, and a switch means for controlling said electrical means and operable to be moved to one position by said second heat motor means, said second heat motor means being operable to be rendered ineffective by said power element to hold said switch means in said one position.

6. In an apparatus for use with a fuel burner having a fluid fuel flow controlling valve, means for actuating the valve to regulate the flow of fuel to the burner, a thrust member operable to engage the valve, a temperature sensitive power element sensitive to the output of the burner, means interconnecting said power element and said thrust member, said power element being operable upon a predetermined high temperature to move said thrust member into engagement with and to move the valve to one position, and means moved by said power element and operable to render said actuating means ineffective.

7. In an apparatus for use with a fluid fuel burner having a flow controlling means, means for actuating the controlling means, a thrust member positioned to operatively engage the flow controlling means, a temperature sensitive power element sensitive to the output of the burner, means interconnecting said power element and said thrust member, said power element being operable upon a predetermined high temperature to move said thrust member into operative engagement with and to move the controlling means to one position, means moved by said power element and operable to render said actuating means ineffective, and means limiting movement of said thrust member by said power element, said interconnecting means including a resilient means so that said power element can have continued movement subsequent to limitation of movement of said thrust member by said limiting means.

8. In an apparatus for use with a fluid fuel burner having a flow controlling means, means for actuating the controlling means, a thrust

member positioned to operatively engage the flow controlling means, a housing, a temperature sensitive power element within said housing and sensitive to the output of the burner, a lever member fulcrumed to said housing and pivotally connected to said element, said thrust member having a pair of spaced abutments, said lever member being operable to engage one of said abutments, a spring member interposed between the other of said abutments and said lever member and operable to urge said lever member into engagement with said one abutment, said power element being operable upon a predetermined high temperature to move said thrust member into operative engagement with and to move the controlling means to one position, means moved by said power element and operable to render said actuating means ineffective, and means limiting movement of said thrust member by said power element, said spring member acting as a lost motion means so that said power element can have continued movement subsequent to limitation of movement of said thrust member by said limiting means.

9. In an oil burner control apparatus, a constant level chamber for supplying oil to the burner, a reciprocal valve supported in said chamber and operable to control the rate of supply of oil to the burner, a container for liquid to be heated by the burner, a temperature responsive control device secured to said container, a lever supported and movable by said device, means in said chamber and limiting the opening movement of said valve to determine the maximum rate of flow of oil, a thrust rod detachably secured at its opposite ends in engagement with said lever and said valve so that said said valve and said lever can have movement in unison, said thrust rod permitting said chamber to be freely removed from cooperative relation to said container and said control device, and means to adjust the effective length of said rod to provide for variation in the distance between said control device and said chamber and so that upon predetermined response of said control device said valve can be moved into engagement with said limiting means.

10. In an oil burner control apparatus, a constant level chamber for supplying oil to the burner, a reciprocal valve supported in said chamber and operable to control the rate of supply of oil to the burner, a container for liquid to be heated by the burner, a temperature responsive control device secured to said container, a lever supported and movable by said device, means in said chamber and limiting the opening movement of said valve to determine the maximum rate of flow of oil, a thrust rod positioned between said lever and said valve, said valve having a stem in end abutting relation to one end of said rod, a sleeve member holding said stem and said rod in alignment, and an adjustable abutment on the other end of said rod and cooperable with said lever to transmit movement of said responsive means to said rod, said adjustable abutment being operable to adjust the effective length of said rod to provide for variation in the distance between said control device and said chamber and so that upon predetermined response of said control device said valve can be moved into engagement with said limiting means, said thrust rod permitting said chamber to be freely removed from cooperative relation to said container and said control device.

11. In an apparatus for controlling an actuated

means having two rates of output, a movable controlling member for said means and normally urged in one direction toward a first position to maintain the output of the means at a first of said rates, a first means for moving said member in a second direction to maintain the output of the actuated means at a second of said rates, a second means for moving said member in said one direction, and lost-motion means interconnecting said second moving means and said controlling means and providing unobstructed movement of said controlling means by said first moving means independently of said second moving means, said second moving means being responsive to the output of the actuated means and operable to take up said lost-motion and to move positively said member in said one direction against the force exerted by said first moving means.

12. In a control apparatus, a first controlling means, a second-controlling means movable relative to said first means, a heat sensitive power means comprising a single element having two separate operating portions, each of said separate portions being operable to exert a force, one of said separate portions being operable to actuate said first controlling means, the other of said separate portions being operable to actuate said second controlling means, a power element operable to move said first controlling means relative to said second controlling means and against the force exerted by said one separate portion, and means operable upon movement of said first controlling means by said power element to render said power means ineffective to actuate said first and said second controlling means.

13. In an apparatus for controlling an actuated means having two rates of output, a movable controlling member for said means and normally urged in one direction toward a first position to 40

- maintain the output of the means at a first of said rates, an electrically energized bimetallic heat motor operable upon energization to move said member in a second direction to maintain the output of the actuated means at a second of said rates, a means for moving said member in said one direction, and lost-motion means interconnecting said moving means and said controlling means and providing unobstructed movement of said controlling means by said heat motor independently of said moving means, said moving means being responsive to the output of the actuated means and operable to take up said lost-motion and to move positively said member in said one direction against the force exerted by said heat motor.
14. In an apparatus for controlling an actuated means having two rates of output, a movable controlling member for said means and normally urged in one direction toward a first position to maintain the output of the means at a first of said rates, an electrically energized bimetallic heat motor operable upon energization to move said member in a second direction to maintain the output of the actuated means at a second of said rates, a means for moving said member in said one direction, lost-motion means interconnecting said moving means and said controlling means and providing unobstructed movement of said controlling means by said heat motor independently of said moving means, said moving means being responsive to the output of the actuated means and operable to take up said lost-motion and to move positively said member in said one direction against the force exerted by said heat motor, and means operable by said moving means for deenergizing said heat motor.
